UNITED STATES PATENT OFFICE.

JOHN C. LYONS, OF McCOMB, MISSISSIPPI.

REINFORCED LOCOMOTIVE-DRIVING-BOX SHOE.

1,178,248.

Specification of Letters Patent.

Patented Apr. 4, 1916.

Application filed August 20, 1915. Serial No. 46,479.

To all whom it may concern:

Be it known that I, JOHN C. LYONS, a citizen of the United States, and a resident of McComb, in the county of Pike and State of Mississippi, have invented certain new and useful Improvements in Reinforced Locomotive-Driving-Box Shoes, of which the following is a specification.

My invention is an improvement in reinforced locomotive driving box shoes, and the invention has for its object to provide a shoe of the character specified, wherein steel reinforcing plates are cast in the shoe, to strengthen and reinforce the same, to prevent damage in use.

In the drawings: Figure 1 is a partial side view of a locomotive provided with the improved shoes; Fig. 2 is a front view of one of the shoes; Fig. 3 is a longitudinal section of Fig. 2; Fig. 4 is a front view of the other shoe; Fig. 5 is a longitudinal section of Fig. 4, and Fig. 6 is a section on the line 6—6 of Fig. 4.

The present embodiment of the invention is shown in connection with the frame 1 of a locomotive, the said frame having a vertical recess or passage 2, in which is arranged the driving box 3, and the shoes to be described are arranged at opposite sides of the recess or passage for engagement by the grooved edges of the driving box 3.

The shaft 4 of the drive wheels 5 is held in the driving box, and the box is mounted for vertical movement in the passage. These shoes, shown in detail in Figs. 2 to 6 inclusive, are cast as a rule from iron, and both shoes are channel-shaped, the one shoe or wedge comprising a body 6, and side walls 7, and the said body is of less thickness at its top, gradually increasing in thickness toward the bottom, as shown, while the side walls have their free side edges parallel and in the same plane. At its lower end

the shoe 6—7 has an undercut notch or recess 8, for receiving adjusting mechanism in the form of a headed rod 9. This rod is threaded through the frame, as shown, and the head of the rod engages the undercut notch 8, and lock nuts 10 are arranged on opposite sides of a bearing clip 11 on the frame through which the rod passes. The rod is threaded as shown, and the shoe may be adjusted by turning the rod 9.

The shoe shown in Figs. 4 to 6 inclusive comprises a body 12 and side walls 13, and

the body 12 is of the same thickness throughout its length. This shoe 12—13 is arranged at the opposite side of the recess or passage 12 from the shoe 6—7, and the side walls 60 of the recess fit in the channels of the shoes, while the flanges of the bearing box 3 engage the sides of the shoes.

Each shoe is reinforced by substantially U-shaped steel plates, each consisting of a body 14 and arms 15 extending at approximately a right angle with respect to the body. Each shoe is provided with three of the plates 14—15, and the bodies of the plates are arranged transversely of the 70 bodies of the shoe, with the arms 15 of the plates in the side walls 7 and 13 of the shoe. In the shoe 6—7 the bodies 14 of the plates are arranged near the inclined inner face of the body 6 of the plate, and in the shoe 75 12—13 the same arrangement holds. That is, the bodies of the plates 14—15 are near the wearing surfaces of the shoe. The body and arms of each plate 14—15 have transverse openings indicated at 16, for permitting the passage of a portion of the cast metal to interlock the plates with the shoes. The plates may be arranged in the mold, and the metal may be poured around the plates, and the molten metal will fill in the 85 spaces between the plates and will pass through the openings 16 to form ties for preventing relative movement of the plate and the shoe and to make the structure practically integral. As shown, five openings 16 90 are provided in the body of each plate, and two openings in each arm of each plate. The free ends of the arms 15 of each plate are flush with the free edge of the adjacent side wall, and the plates are hidden and 95 concealed within the bodies of the shoes. The openings are omitted at the connections between the bodies and the arms of the plates, in order to preserve the full strength of the plates at this point.

I claim:

1. A locomotive driving box shoe of channel shape and composed of cast metal, and comprising a body and side walls extending laterally from the body, a series of reinforcing plates of steel embedded in the material of the shoe, said plates each comprising a body arranged transversely of the body of the shoe, and arms extending laterally from the body and embedded in the side walls of 110 the shoe, said plates being arranged at the ends and intermediate the ends of the shoe

and having transverse openings to permit the passage of the material of the shoe through the openings, the free ends of the arms of the plates being flush with the free edges of the side walls of the shoe.

2. A locomotive driving box shoe of channel shape, and composed of cast metal, and comprising a body and side walls extending laterally from the body, a series of reinforcing plates of steel embedded in the material of the shoe, said plates each comprising a body arranged transversely of the body of the shoe, and arms extending laterally from the body and embedded in the side walls of the shoe, said plates being arranged at the ends and intermediate the ends of the shoe and having transverse openings to permit the passage of the material of the shoe through the openings.
3. A locomotive driving box shoe of channel shape, and composed of cast metal, and comprising a body and side walls extending

laterally from the body, a series of reinforcing plates of steel embedded in the material of the shoe, said plates each comprising a body arranged transversely of the body of the shoe, and arms extending laterally from the body and embedded in the side walls of the shoe.

4. A locomotive driving box shoe of channel shape and composed of cast metal, and composed of a body and side walls extending laterally from the body and a reinforcing plate of steel embedded in the material of the shoe, each plate comprising a body arranged transversely of the body of the shoe, and arms extending laterally from the body and embedded in the side walls of the shoe.

JOHN C. LYONS.
